UNITED STATES PATENT OFFICE

155,472

DESIGN FOR AN ELECTRIC CUBE TAP

Arthur N. Bec Var, Bridgeport, and Robert Earl Munz, Fairfield, Conn., assignors to General Electric Company, a corporation of New York

Application June 15, 1948, Serial No. 146,990

Term of patent 14 years

(Cl. D26—1)

To all whom it may concern:

Be it known that we, Arthur N. Bec Var and Robert Earl Munz, citizens of the United States, residing respectively at Bridgeport, in the county of Fairfield, State of Connecticut, and Fairfield, in the county of Fairfield, State of Connecticut, have invented a new, original, and ornamental Design for an Electric Cube Tap, of which the following is a specification, reference being had to the accompanying drawing, forming a part thereof.

Figure 1 is a perspective view of an electric cube tap showing our new design, and

Figure 2 is an end elevation thereof.

The characteristic and dominant features of

our design reside in the portions shown by the full lines in the drawing.

We claim:

The ornamental design for an electric cube tap, as shown and described.

ARTHUR N. BEC VAR.
ROBERT EARL MUNZ.
